UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

COMPRESSOR MECHANISM.

Application filed December 16, 1924. Serial No. 756,278.

This invention relates to compressor mechanism.

It has for its object to provide an improved compressor mechanism. A further object is to provide an improved portable compressor mechanism particularly adapted for mines. The several elements which go to make up the portable compressor are so arranged that the maximum height of the device will be extremely low and it is preferable that the height will not exceed the maximum height of one of the elements which is already of minimum height. Such an element herein specifically comprises the electric driving motor for the compressor, but it will be clear that any other element might be chosen. It is especially desirable that an extremely low compressor outfit be provided, for it will be understood that this outfit must operate at 20 times in coal seams which are extremely low. It is accordingly the further object of my invention to provide an improved arrangement of parts by which an extremely low and compact outfit is obtained. It is also a further 25 object to provide in a portable mine compressor an improved compressor having an improved arrangement with respect to the truck frame upon which the several elements are arranged. Herein the compressor is of the two cylinder opposed type disposed transversely of the truck frame and tracks upon which the truck is mounted, thus reducing vibration of the truck to a minimum and permitting the more successful use of a transverse reciprocating type of compressor. 30 However, my improved arrangement also permits the more successful use of an ordinary type of single cylinder compressor, if arranged to have the piston thereof reciprocate in a transverse direction. The inherent unbalance of this type of compressor would tend to cause transverse movement of the truck, but the rails would tend to hold the same against any appreciable amount of 35 movement, thereby cutting down vibration. While my improved arrangement is well adapted to this single cylinder type of compressor, yet by employing an opposed type of compressor, still further advantages are obtainable. For instance, in some cases, the tracks may be old and improperly spiked in which case the single cylinder compressor would only make matters worse, for there would be a tendency to shove the rails laterally or possibly to spread the same if the com-

pressor outfit should remain in a single position any length of time. It will thus be seen that it is highly desirable to reduce the maximum amount of transverse vibration in these cases, but it is also highly desirable to use a transversely disposed compressor in order to obtain the compact arrangement. This dual result, among others, is obtained by the use of an opposed compressor of the general type herein shown. My improved arrangement also permits the ready adaptation of the usual auxiliary elements such as the cooling water tank for the compressor, the electric controller box for the compressor motor, and also the positioning of the air receiver. To further accomplish the compact arrangement it has been found desirable to suspend certain of the elements so as to extend below the level of the truck frame and in some instances to mount the frame upon dropped axles, thus rendering the device extremely low and compact.

In the accompanying drawings I have shown for purposes of illustration one form which my invention may assume in practice.

In these drawings,—

Fig. 1 is a plan view of the assembled mine compressor.

Fig. 2 is a side elevation thereof.

Fig. 3 is a vertical section taken on line 3—3 of Fig. 1.

Fig. 4 is a fragmentary view of a drop axle.

Fig. 5 is a view of a straight axle.

Fig. 6 is a view showing a wheel mounting adapted for narrow gage tracks.

Fig. 7 is a detail view showing my improved means for supporting one of the compressor elements.

In the illustrative embodiment of my invention I have shown a truck frame 1 having usual side flanges 2, end flanges 3, and a bottom portion 5 upon which the several elements of the compressor may be mounted. While most of the elements of the compressor outfit may be supported at the level of the frame, it will be understood that the bottom 5 may have cut out portions in order to allow certain of the elements to project through said openings to below the level of the frame, thereby obtaining a rather low construction. The term "prevailing level of the frame" which is used in the claims is meant to specify the level at which most of the elements of the compressor outfit are carried. Usual coupling elements 6 are carried on each of the

end flanges 3. Any suitable type of axle may be used for supporting the frame. For example, there is shown in Fig. 4, a drop axle 7 carrying usual wheels 8 adapted to run upon the usual mine rails 9. It will be noted that the axles as shown in Fig. 2 are so disposed relative to the frame as to form a substantially balanced outfit when the several elements are mounted thereon.

In order to obtain my improved compact arrangement I have disposed the electric motor 10 in a central position with its axis extending longitudinally of the frame; and this motor may be of any usual type but is preferably of the slow speed type adapted to be directly connected to a transversely disposed compressor 11, as through a usual fly wheel connection 12. The compressor 11 herein is of the two-cylinder opposed type having a crank case 13 disposed centrally of the truck frame approximately in the center thereof. Mounted on opposite sides of the crank case are cylinders 14 and 15 whose longitudinal axes are offset from each other in order to obtain the opposed reciprocating action of the pistons 16 and 17 actuated by a suitable two-throw crank shaft 18 which as before mentioned is directly connected to the driving motor 10. Usual type of unloading mechanisms 19 and 20 are mounted on the cylinder heads. This type of unloading mechanism is more fully disclosed in my co-pending application, Ser. No. 706,583, filed Apr. 14, 1924, and is particularly adapted to my present arrangement in that the longitudinal axis thereof extends vertically. The unloading mechanisms are of the air controlled type actuated by pressure fluid from a receiver 21 as by suitable pipe connections 22 and 23 leading from a pilot valve 24 of any usual type, in turn connected to the receiver by a pipe 25. Fluid conducting means constituting pipes 40 and 41 lead from the respective cylinders to a receiver 21 from which leads a usual discharge pipe 42.

It will be noted that the receiver is disposed transversely of the truck frame and set below the upper edge of the flanges thereof as is also the motor and compressor. Suitable vertical abutments 26 are provided on the bottom 5 upon which the receiver is set to thereby steady and support the same. The receiver is held in place by an inverted U-shaped bolt passing over the top thereof and the free ends of which extend through the bottom 5 and are held by nuts 26' on the lower side of the bottom 5 of the frame.

With the arrangement thus far it will be seen that the motor, compressor and receiver provide in effect a T-shaped arrangement thus leaving ample space parallel to the motor and laterally thereof for the positioning of other necessary auxiliary elements, such as a water cooler 27 connected to the cooling jackets 28 of the compressor cylin-

ders. As shown herein, an outflow pipe 29 is connected to a usual circulating pump 30, the pump pulley 33 being driven by a belt 31 driven from a flywheel pulley 32. Leading to the lower side of the cylinder 15 from the pump is the pipe 34, while leading from the upper side of said cylinder to the lower side of the cylinder 14 is a pipe 35. A return pipe 36 leads from the upper side of the cylinder 14 to the cooling tank 27. It will thus be seen that the transverse disposition of the compressor allows a very compact arrangement of the piping just mentioned and means for driving the circulating pump. On the side of the motor opposite the cooling tank 27 is disposed the motor controller 27 and any other necessary electrical equipment.

It will thus be seen that my improved arrangement permits reduction of the over-all dimensions of the truck, and yet by the use of a transversely disposed compressor any tendency to shake the compressor outfit is reduced to a minimum. By the use of an opposed type compressor any tendency to spread the tracks or loosen the same is also reduced to a minimum, if not wholly eliminated; while the particular arrangement of the directly connected motor, although it will be understood that direct connection is not necessary, brings about a very well balanced machine which is approximately symmetrically balanced with respect to the longitudinal axis. Thus this arrangement distributes the load equally on each track, and also permits the ready adaptation of the other necessary auxiliary elements such as the cooling water tank and the electrical apparatus.

In Fig. 5 I have shown a modified form of wheel mounting comprising a straight axle 43; whereas in Fig. 6 I have shown a wheel mounting comprising spaced wheel supports 44 carried on the lower side of the bottom 5 of the frame 1. This latter construction is particularly adapted for narrow gage tracks or where it might be desired to vary the gage of the wheels.

While I have in this application specifically described several forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a portable compressor mechanism, a portable base frame, a horizontal motor mounted thereon and disposed in the longitudinal center thereof, a horizontal compressor driven by said motor, said compressor having horizontal cylinders extending transversely at each side of the longitudinal cen-

ter of said frame, and a transversely disposed tank for receiving the fluid discharged from said compressor, the combined height of said base frame and said motor determining the 5 height of the mechanism.

2. In a portable compressor mechanism, a portable base frame having a recessed portion, a horizontal motor thereon, a horizontal-cylndered compressor driven by said 10 motor, and a horizontally disposed tank for receiving the fluid discharged from said compressor, said motor, compressor, and tank being disposed with portions thereof below the upper portion of said frame and within said 15 recessed portion, the combined height of said base frame and said motor determining the height of the mechanism.

3. In a portable compressor mechanism, a portable base frame having wheeled axles 20 and a platform, said axles and platform being in substantially the same horizontal plane, a horizontal motor mounted on said platform and having a portion thereof depending below the same, a horizontal compressor driven 25 by said motor, and a horizontally disposed tank for receiving the fluid discharged from said compressor.

4. In a portable compressor mechanism, a portable base frame having wheeled axles 30 and a platform, said axles and platform being in substantially the same horizontal plane, a horizontal motor mounted on said platform and having a portion thereof extending through said platform to a point below a horizontal plane including the axes of said 35 wheels, a horizontal compressor driven by said motor, and a horizontally disposed tank for receiving the fluid discharged from said compressor, the combined height of said base 40 frame and motor determining the height of the mechanism.

5. In a portable compressor mechanism, a base frame comprising supporting wheels 45 movable over a trackway, said frame provid-

ing a supporting surface substantially at the 45 level of the axes of said supporting wheels, a compressor thereon, and a driving motor for said compressor supported by said frame so that the motor base is substantially as low as the axes of the wheels of said frame, said 50 compressor being mounted on said supporting surface and extending only within the vertical limits of the motor.

6. In a portable compressor mechanism, a base frame comprising supporting wheels 55 movable over a trackway, said frame providing a supporting surface substantially at the level of the axes of said supporting wheels, a compressor element thereon, and a driving motor element therefor, said frame being 60 formed with an opening through which a portion of the taller of said elements projects, the other of said elements being mounted on said supporting surface so that the same is disposed within the vertical limits of that one 65 of said elements which extends through said frame.

7. In a portable compressor mechanism, a portable base frame, a horizontal motor mounted thereon and disposed in the longitudinal center thereof, a horizontal compressor driven by said motor, said compressor having horizontal cylinders extending transversely at each side of the longitudinal center of said frame, and a transversely disposed 70 tank for receiving the fluid discharged from said compressor.

8. In a portable compressor mechanism, a portable base frame having a recessed portion, a horizontal motor thereon, a horizontal-cylndered compressor driven by said motor, and a horizontally disposed tank for receiving the fluid discharged from said compressor, said motor, compressor, and tank being disposed below the upper portion of said 80 frame and within said recessed portion.

In testimony whereof I affix my signature.

FRED D. HOLDSWORTH.
